UNITED STATES PATENT OFFICE.

GEORGE R. WYMAN, OF EAST WALPOLE, MASSACHUSETTS, ASSIGNOR TO CHARLES S. BIRD, OF EAST WALPOLE, MASSACHUSETTS.

APPARATUS FOR SUPPLYING WATERPROOFING MATERIAL TO PAPER.

1,152,136.

Specification of Letters Patent. Patented Aug. 31, 1915.

Application filed December 23, 1914. Serial No. 278,465.

To all whom it may concern:

Be it known that I, GEORGE R. WYMAN, a citizen of the United States, residing at East Walpole, in the county of Norfolk and State of Massachusetts, have invented certain new and useful Improvements in Apparatus for Supplying Waterproofing Material to Paper, of which the following is a specification, reference being had to the accompanying drawings, forming part thereof.

This invention has reference to improvements in apparatus for supplying asphaltic and other waterproofing or water resisting material to paper or other fabric.

15 The main object of this invention is to supply the waterproofing or water resisting material at a high temperature without danger of igniting the same.

Another object of the invention is to provide means for raising the temperature of the waterproofing or water resisting material by a step by step process whereby said material at one of its heating steps may be raised to a temperature less than its flashing point and, at a subsequent heating step, may be raised to a temperature equal to or exceeding its flashing point without danger of ignition.

Other objects of the invention will appear from the following description.

The invention consists in such novel features of construction and combination of parts as shall hereinafter be more fully described and pointed out in the claim.

20 Figure 1 of the drawing illustrates a simple apparatus embodying the present invention; the same being shown in side elevation partially broken away and parts being shown in section. Fig. 2 shows a modified construction of the supply pipe at the second heater.

Similar characters of reference designate corresponding parts throughout.

25 The waterproofing or water resisting material herein more particularly referred to usually contains asphaltum, oils, tar or bituminous material of some kind.

By the term waterproofing material it is my purpose to designate any material adapted in its fluid state to be applied to paper, fabric or other material or articles for the purpose of protecting said paper, fabric, material or article from moisture in some degree.

30 The fluidity of most waterproofing com-

pounds, particularly those containing tar or asphaltum, is increased by raising the temperature of such compounds above the flowage point. In order to obtain the best results in supplying such waterproofing compounds to materials and particularly to paper it is of course desirable that the water-proofing be so fluid that it will quickly saturate the paper and that a large proportion of such compound will be absorbed by the fibers of the paper while the surplus of such compound not thus absorbed is in such a fluid condition that it can readily drain from the paper. In practice it is found that to obtain the most desirable degree of fluidity of asphaltic waterproofing compounds for their application to paper it is usually necessary to raise the temperature of such compounds approximately to their flashing points and, sometimes, preferably above such flashing points. Such heating of the compound approximately to the flashing point, with the apparatus heretofore employed for that purpose is dangerous owing to the fact that the vessel containing the compound must be heated to a temperature above that of the compound and, hence, if a portion of said vessel becomes exposed adjacent to said heated compound any slight accumulation of volatile matter from the compound may become ignited from such exposed portion of the vessel and the contents of said vessel may thus be set on fire.

In the present invention provision is made for raising the temperature of the waterproofing compound or material to any degree within the limit of temperature at which said compound can be utilized in a practical manner and wholly without reference to the flashing point of such compound or material.

The invention as embodied in the apparatus shown in the drawing preferably includes the tank or vessel 5 which may be of any convenient size and adapted to contain a large amount of the waterproofing compound or material. Heat is applied to this vessel 5 by a primary heater shown on the drawing by the furnace 6 and this heat is so controlled that the material in the vessel 5 is raised to a temperature preferably not exceeding 400° Fah. that is to a temperature to render the waterproofing compound sufficiently fluid to readily flow, but not to the flashing point. From the vessel 5 the com-

compound or material thus pre-heated flows through the pipe 7 which is preferably provided with the drum or enlargement 8, where said material is subjected to heat from the secondary heater device 9 to raise the temperature of said compound or material preferably above the temperature it has attained in the vessel 5. From the pipe 7 or its enlargement 8 the finally heated material flows through the steam jacketed pipe 10 to the pan 11 which is open at its top and has the guide rolls or devices 12, 12 adapted to guide the web α - α through the fluid material in said pan.

15 It is to be understood that the supply of the waterproofing compound or material maintained in the vessel 5 is sufficient during operations of the apparatus to fill the pipe 7, its enlargement 8 and pipe 10 and that the flow of such compound or material to pan 11 is adapted to be controlled by the valve 10' of pipe 10. As the enlargement 8 of pipe 7 is thus completely filled and air is excluded it is evident that the temperature 25 of the material in said enlargement 8 can be raised above the flashing point of said material and as a result the material is delivered to the pan 11 in a condition of extreme fluidity in which condition it is most readily 30 absorbed by the web α - α so that it is practicable to move said web through said pan much more rapidly than heretofore. The extreme fluidity of the waterproof material supplied to the web α - α also facilitates the 35 draining of the surplus material from said web as said web is guided from the pan 11.

While I have shown the pipe 10 as supplied with a steam jacket 13 it is to be understood that the steam to be supplied thereto 40 through pipe 14 is merely to assist in maintaining the temperature of the material passing through said pipe, that is to protect said pipe from the lower temperature of the atmosphere. In practice I have not found it 45 practicable to supply steam to the jacket of pipe 10 at a temperature exceeding 350° Fah. while, as above indicated, the waterproofing material supplied through said pipe 10 should be at a temperature above 400° 50 Fah.

In the drawings I have shown the apparatus as provided with walls whereby the live flames of the primary heater 6 and the secondary heater 9 are insulated or shut off from any possible ignition of gases escaping 55 from the material in the pan 11 but said walls are not essential to the practical operation of the apparatus.

As a provision for circulating the fluid from the pan 11 to some convenient or desirable point beyond said pan I have shown said pan 11 as provided with the valved outlet pipe 15 but this pipe is not necessarily essential to the operation of the device.

It is to be understood that the device is 60 not limited to the use of the enlargement 8 of pipe 7 as heat may be applied directly to some portion of pipe 7 and pipe 10 may be and practically is a continuation of pipe 7.

In the modification shown in Fig. 2 of 70 the drawings pipe 7 is shown as having the jacket 16 to confine a layer or body of sand around said pipe 7 whereby any leakage from a joint in pipe 7 may be received by such sand. In the practical operation of the 75 apparatus however it is immaterial whether the heat generated at or by heating device 9 is applied directly to the pipe 7 or to some member exterior of such pipe 7 provided it is possible thereby to raise the temperature 80 of the material in pipe 7 to or above 400° Fah.

Having thus described my invention I claim as new and desire to secure by Letters Patent—

85 Apparatus for supplying waterproofing material to articles such as paper comprising means for raising the temperature of the material to a point below its flashing point, means for receiving such initially heated material and excluding air therefrom, means for raising the temperature of said pre-heated material to a point above its flashing point, and a receptacle for said heated material adapted also to receive the article to 95 which said material is to be supplied.

GEORGE R. WYMAN.
